UNITED STATES PATENT OFFICE.

B. G. BRIGGS, OF PROVIDENCE, RHODE ISLAND, ASSIGNOR TO HIMSELF
AND T. HILTON, OF SAME PLACE.

DESIGN FOR A PAPER COLLAR.

Specification forming part of Design No. 2,344, dated July 3, 1866.

To all whom it may concern:

Be it known that I, B. G. BRIGGS, of the city and county of Providence, State of Rhode Island, have invented a new and ornamental Design for Paper Collars; and I do hereby declare that the following is a full, clear, and exact description thereof, which will enable others skilled in the art to make and use the same, reference being had to the accompanying drawing, forming part of this specification.

The drawing represents an elevation of this invention.

This invention consists in ornamenting a paper collar by a series of bars placed close together with square ends at the bottom and rounded at the top, in combination with a ridge and seam extending over the series of bars in such a manner as to produce a collar of novel and ornamental appearance.

A represents a collar, which is ornamented by a series of upright bars, a, placed close together and provided with square ends at the bottom, but rounded on top, as shown. Over the bars and at a certain distance from their rounded ends extends a ridge, b, representing a seam, and by the whole combination an ornament for a collar is obtained, which gives to said collar a novel and elegant appearance.

What I claim as new, and desire to secure by Letters Patent, is—

The design for paper collars, as shown and described.

The above specification of my invention signed by me this 23d day of May, 1866.

B. G. BRIGGS.
